UNITED STATES PATENT OFFICE

LUCIAN M. ZELL, OF ESSEX COUNTY, NEW JERSEY

DESIGN FOR A PRECIOUS OR A SEMIPRECIOUS JEWEL OR SIMILAR ARTICLE

Application filed March 19, 1931. Serial No. 39,153. Term of patent 14 years.

To all whom it may concern:

Be it known that I, LUCIAN M. ZELL, a citizen of the United States, and a resident of New Jersey, in the county of Essex and State of New Jersey, have invented a new, original, and ornamental Design for a Precious or a Semiprecious Jewel or Similar Article, as shown, of which the following is a specification, reference being had to the accompanying drawings, forming part hereof.

Figure 1 is a plan view of a precious or semiprecious jewel or similar article, showing my new design;

I claim:

The ornamental design for a precious or a semiprecious jewel or similar article, as shown.

LUCIAN M. ZELL.
